UNITED STATES PATENT OFFICE.

JOHN FEDRAN, OF EAST PITTSBURG, PENNSYLVANIA.

COMBINATION FURNITURE.

No. 821,349.

Specification of Letters Patent.

Patented May 22, 1906.

Application filed January 17, 1906. Serial No. 296,542.

To all whom it may concern:

Be it known that I, JOHN FEDRAN, a citizen of the United States of America, residing at East Pittsburg, in the county of Allegheny and State of Pennsylvania, have invented 5 certain new and useful Improvements in Combination Furniture, of which the following is a specification, reference being had therein to the accompanying drawings.

10 This invention relates to certain new and useful improvements in combined beds and tables; and the invention has for its object to provide a folding structure which can be easily used as a bed or folded to be used as a table.

Another object of this invention is to provide a combined bed and stand which can be easily and quickly folded into either article and which will be extremely simple in construction, strong and durable, and comparatively inexpensive to manufacture.

Briefly described, my improved combined article consists of two frames, which are connected together by sections of rails that are 25 pivotally connected together. Plates are pivotally connected to the outer ends of the frames, said plates being supported in a horizontal position by the sections of rails when a table is to be formed, while the plates are 30 folded upon the frames when the structure is to be used as a bed.

The detail construction of my improved combined article will be hereinafter more fully described and claimed and then specifically pointed out in the claims, and, referring 35 to the drawings accompanying this application, like numerals of reference designate corresponding parts throughout the several views, in which—

40 Figure 1 is a side elevation of a table constructed in accordance with my invention. Fig. 2 is an end view of a bed formed from the structure of the table illustrated in Fig. 1. Fig. 3 is a side elevation of a bed, and Fig. 4, 45 detail views of the pivotal connection formed between the sections of the rails of my improved bed.

To put my invention into practice, I preferably construct my improved combined table and bed of light and durable metal; but it is obvious that other materials may be readily used in lieu of the metal. The structure embodying the table and bed consists of two frames 1 and 2, each frame consisting of posts 50 3 3, which are connected together by transverse rods 4 and 5. In the form of a table

the frames 1 and 2 serve as legs for supporting a table-top, while in the formation of a bed the frames 1 and 2 serve as head and tail pieces of the bed.

Pivots mounted upon the rods 4 4 of the frames 1 and 2 are plates 6 and 7, said plates being provided with pierced lugs 8 8, through which the rods 4 extend. The plates serve as a table-top, and in order to support said 65 plates in a horizontal position, the frames 1 and 2 are connected together by rails 9 9. The posts 3 3 of each frame are provided with outwardly-extending pierced lugs 10 10, and pivotally connected to said lugs are sections 70 11 11, the free ends of said sections being pivotally connected to a common section 12, the sections 11 11 and 12 forming the rails 9 9 of a bed. When a table structure is formed, the sections 11 11 are folded upwardly 75 against the posts 3 3 of each frame, and the common section 12 of each rail forms supports for the plates 6 and 7, the frames 1 and 2 having been moved together to form a substantially rectangular structure.

As a bed the plates 6 and 7 are folded downwardly upon the inner sides of the frames, as clearly illustrated in Fig. 4, and in order to support the frames 1 and 2 in a vertical position and maintain rigid rails 9 9 I 85 pivotally connect the sections of the rails together, as illustrated in Fig. 4 of the drawings. It will be observed that the ends of the common section 12 are provided with lugs 14, which engage shoulders 15, carried by 90 the sections 11 11. In this manner it will be impossible to break a joint between the sections 11 and 12 otherwise than moving said sections upwardly to form bridges to support the plates 6 and 7.

To maintain the table in the form shown in Fig. 1 of the drawings, I provide the sections 11 11 and the posts 3 3 of each frame with eyelets 16 16, and engaging in said eyelets are yokes or links 17 17, said links being 100 adapted to retain the sections 11 11 in engagement with the posts when in parallel alignment with one another.

From the foregoing it will be observed that I have devised a strong and durable structure which can be readily used as a table or bed as the occasion may demand and as constructed may be easily and quickly manipulated to form either article.

Such changes in the construction and manipulation of my improved combined bed and table as are permissible by the appended

claims may be resorted to without departing from the spirit and scope of the invention.

What I claim, and desire to secure by Letters Patent, is—

- 5 1. A combined table and bed structure embodying two frames, plates pivotally connected to the upper ends of said frames and adapted to form a table-top, sectional rails carried by said frames and adapted to fold 10 upwardly to support said plates, means to hold said rails in a rigid position, and means to hold parts of said rails in horizontal alignment with said frames, substantially as described.
- 15 2. An article of furniture convertible into a table and a bed, comprising a pair of frames each embodying vertical legs, tie-rods connecting the legs of each frame, plates pivotally hung on said tie-rods and acting in one 20 position to form a table-top and in another position to act as a head-piece and foot-piece respectively of a bed, and sectional rails piv-

totally connected to the frames and acting in one position to support the table-top and in another position acting as the side rails of a bed.

3. The combination with frames, of plates pivotally attached to said frames, and sectional side rails pivotally connected to said frames and acting both as side rails of a bed 30 and as a support for the plates to form a table-top.

4. In an article of furniture, two frames, plates pivotally attached to said frames, and supporting-rails, each formed in three sections pivoted together and to the frames, as and for the purpose described.

In testimony whereof I affix my signature in the presence of two witnesses.

JOHN FEDRAN.
